SELVAGE FORMING MECHANISM FOR
NEEDLE LOOMS

Philip Worth Robinson, Ombersley, England, assignor to T. Bond Worth & Sons Limited, Severn Valley Mills, Stourport on Severn, England, a British company

Application December 7, 1948, Serial No. 63,870
In Great Britain December 10, 1947

15 Claims. (Cl. 139—124)

1

This invention relates to looms wherein double shot wefts are inserted in pairs through the warps by a pair of weft needles. Such looms will hereinafter be referred to as looms of the kind specified.

In my co-pending application for a patent numbered 760,805, filed July 14, 1947, there is described a method of and means for binding in the looped ends of double shot needle inserted wefts after each is successively inserted through the warps, such method eliminating the use of shuttles commonly employed to pass a line of selvedge thread through such looped ends.

The object of the present invention is to provide a method of and means for inserting selvedge thread through the pair of looped ends of a pair of double shot needle inserted wefts after each such pair is successively inserted through the warps.

It is a further object of the present invention to provide selvedge forming mechanism in or for a loom of the kind specified, which selvedge mechanism incorporates means for splitting one of the double shot needle inserted wefts to enable pile threads to be inserted into the fabric between the individual weft shots constituting the double shot, said means being adapted to release said weft shots at the required time to permit the usual beating-up action of the loom to be performed.

Still another object of the invention is to provide in or for a pile fabric loom, for instance, a carpet loom, characterised by a considerable distance between the point where the weft is delivered and the point where it is eventually held in the warps, that is to say, a long beat-up, selvedge forming mechanism which includes means for transferring the looped weft ends from the first to the second position at which they are registered with each other with portions of their openings in alignment with each other, so that selvedge thread can then be inserted through these aligned loops and does not subsequently undergo appreciable displacement with resultant loosening or other undesirable effects on the selvedge as a result of the beating-up action of the loom.

It is a further object of the invention to provide selvedge forming mechanism incorporating means for positioning precisely weft and selvedge thread loops to permit the passing therethrough of a further selvedge thread loop with certainty in operation notwithstanding slight irregularities in the jute commonly used for the weft.

Further objects of the invention and advan-

2

tages thereof will appear or will be pointed out in the remaining part of the specification or in the claims appended thereto.

In the accompanying drawings there is shown 5 in or for a loom of the kind specified one embodiment of selvedge forming mechanism according to the present invention, and there is also diagrammatically shown the performance of the new or improved method according to the invention.

Referring to the drawings:

Figure 1 is a diagrammatic plan view showing 10 a pair of weft loops in the process of being carried by their respective weft hooks towards an alignment station, the relative positions of the previously inserted selvedge thread loop and the selvedge thread needle also being indicated.

Figure 2 is a similar diagrammatic plan view 15 showing the pair of weft loops in alignment, a selvedge thread loop having been passed through them and the selvedge thread needle in the process of retraction.

Figure 3 is a plan view of selvedge forming 20 mechanism constructed in accordance with the invention in the position in which the weft needles are just about to enter the guide block of the selvedge forming mechanism.

Figure 4 is a view of the same mechanism in 25 side elevation viewed from the direction in which the weft needles approach the mechanism.

Figure 5 is a sectional view on the line 5—5 of Figure 3.

Figure 6 is a fragmentary view in side elevation 30 showing the guide block in section on the line 6—6 of Figure 3 and the positioning plate.

Figure 7 is a sectional view in end elevation on the line 7—7 of Figure 3 of the guide block with the weft needles received in their respective guide openings and the weft hooks in the position 35 prior to engaging weft loops.

Figure 8 is a view in end elevation of the guide 40 plate viewed in the forward direction of travel of the weft hooks and showing the weft loops aligned around the opening in the guide plate and positioned by the projection thereof.

In the construction of selvedge forming mechanism as shown in the drawings, the mechanism is intended for application to a loom for weaving pile fabrics wherein there is inserted simultaneously an upper double shot of weft 10 and a lower double shot of weft 11. The weft-inserting needles 12 and 13, Figure 7, are connected to a conventional form of mechanism, not shown in the drawings, to move them in the known manner transversely through the warps, the upper

needle 12 carrying a double shot of weft through the upper shed formed by the centrally disposed stuffer warps 14, and the upper binding chains and the lower needle 13 carrying a double shot of weft 11 between the stuffer warps 14 and the lower binding chains.

In the diagrams shown in Figure 1 and Figure 2, the upper and the lower binding chains are omitted to simplify the disclosure and the positions of the weft loops are shown relatively to the stuffer warps 14 which are not moved transversely to the thickness of the fabric during shedding operations of the loom.

It will be understood that the loops or double shots of weft 10 and 11 are shown in the diagrams as single loops, for the sake of clarity, but, if desired, each of these loops may be duplicated, using a double weft thread instead of a single weft thread to form each loop this being frequently done where it is required to give the pile fabric, such as a carpet, extra weight and stiffness.

It will be further understood that at the edge of the fabric remote from that at which the selvedge mechanism operates the weft is carried around the last warp of the binding chains by reason of the shedding of the binding chains intermediate each withdrawal and insertion of the weft needles from and into their respective sheds so that at this edge of the fabric the weft is automatically bound-in without the necessity for the provision of separate selvedge forming mechanism. It is only at the edge of the fabric nearest the leading end of the weft needles at which such a separate mechanism for selvedge forming is required because of the impossibility of shedding the binding chains whilst the weft needles remain in the sheds to hold the weft loops or double shots of weft in position.

In performing the method of the invention, a pair of double shots of weft are inserted in the usual manner by weft needles 12 and 13 travelling through their respective sheds. These loops are held with portions of their openings in alignment with each other by a pair of weft hooks 14a and 15, as indicated in Figure 2.

In this position a selvedge thread needle 17 passes through the aligned weft loops carrying with it a selvedge thread 18 which is engaged by a selvedge thread hook 19 and retained on the hook to form a selvedge thread loop 20, as seen in Figure 2, whereupon the needle 17 is retracted.

The aligned weft loops are subsequently released whilst the selvedge thread hook 19 retains the selvedge thread loop 20 in the path of the needle 17 and the released weft loops are then drawn, as shown at 21, by reason of the usual tensioning applied to the weft thread around the base of the retained selvedge thread loop 20.

In the next succeeding cycle of operations the needle 17 passes through the next pair of weft loops held in alignment at the station 16, see Figure 2, and also passes through the retained weft loop 20. In this position the selvedge thread hook 19 executes a lateral movement towards the edge of the fabric, releases the retained loop 20 and subsequently makes a return stroke away from the edge of the fabric passing between the selvedge thread needle 17 and the associated part of the selvedge thread 18 lying along the needle so as to engage and retain a fresh selvedge thread loop 21. The needle 17 is then retracted and the sequence of operations repeated so as to form a chain of selvedge thread loops the bases of

which are encircled by weft loops, each selvedge thread loop itself encircling the base of the next succeeding selvedge thread loop, as seen in Figure 1.

It will, of course, be understood that it is not necessary that the selvedge thread hook 19 should necessarily execute movements towards and away from the edge of the fabric in carrying out the method of the invention. It could, for instance, operate in a plane at right angles to the plane of the fabric. Furthermore, it is not essential that the selvedge thread needle 17 should move, as shown in Figures 1 and 2, in the plane of the fabric and parallel to the edge thereof. It could, for instance, operate at right angles to this plane, in which case the selvedge thread hook 19 would be positioned on the side of the aligned weft loops opposite to that of the needle in its retracted position and the needle 17 could be either above or below the fabric.

In selvedge forming mechanism for carrying out the method of the invention as shown in the drawings, there is arranged at the side of the fabric at which the selvedge is to be formed a guide block 22 in which there are provided two openings spaced one above the other the upper, 23, for receiving the leading end of the upper weft needle 12 and the lower, 24, for receiving the leading end of the lower weft needle 13. The entrances of these openings are flared, as seen at 25 and 26, so that if for any reason the weft needles are deflected somewhat from their proper courses they are guided by the flared side walls into the openings 23 and 24.

These guide openings 23 and 24 in the guide block serve to prevent lateral deflection of the weft needles 12 and 13 whilst the weft hooks 14a and 15 are drawing loops of weft laterally away from the needles. It will be appreciated that the weft is in tension by reason of tension means of the conventional kind provided on the loom at the opposite edge of the fabric from the selvedge-forming mechanism and consequently a considerable transversely acting deflectional force is set up on each of the weft needles by the aforesaid action of the weft hooks.

The guide block also includes a guide opening 27 which extends through the guide block in a direction approximately parallel to the edge of the fabric in which opening the base portion 28 of the selvedge thread needle 17 can reciprocate.

Each weft needle is provided with the usual eye or opening, as seen at 29, Figure 3, through which the weft thread passes and is further provided with a recess or gap near its forward end to enable the weft thread to be drawn laterally away from the needle by the weft hooks. As seen in Figure 7, the weft loop 10 of the upper weft needle is spaced away from the base 30 of the gap in this needle leaving an opening through which the upper weft hook can operate, and similarly the loop of weft thread 11 is spaced away from the base 31 of the gap in the lower needle, this gap being longer than that in the upper weft needle to accommodate an auxiliary presser member 32 attached to the lower weft hook, for a purpose to be later described.

The weft hook means in the embodiment of mechanism shown in the drawings, is in the form of two hooked members one of these, the upper weft hook 14a, being adapted to engage weft from the upper weft needle 12 and the other, 15, being adapted to engage weft from the lower weft needle 13.

The upper hooked member 14a comprises an

arm 33 pivotally mounted so as to be rotatable about a vertical axis, spaced laterally from the guide block on that side of it remote from the fabric, the hooked portion of said member being formed integrally with the arm 33 and comprising a small, upstanding lug 34 at the forward end of the arm, said lug being provided with a nose 35 projecting forwardly from the lug in the direction in which the hooked member carries weft from its associated weft needle.

The arm 33 incorporates a telescopic adjustment for length comprising clamping bolts 36 engaging in one telescopic part and passing through slotted openings in the other telescopic part to permit the nose of the arm to be adjustable in position so as to pass centrally through the gap near the end of the upper weft needle when this is at its limit of travel into its associated shed and, when the arm is turned on its pivotal mounting, the nose 35 travels in an arcuate path approximately parallel to the edge of the fabric and carries the lower shot or thread of weft loop picked up from the upper needle towards and to an alignment station level, or approximately level, to the fell of the fabric, the latter being indicated at 37, Figure 3, the upper shot of this loop or thread remaining in its former position held by the weft needle 12.

The lower hooked member 15 comprises a somewhat similar assembly but in this case is formed of an arm 38 pivotally mounted on a horizontal axis at the lower end of the arm, the hooked portion being formed by a forwardly projecting nose 39 which is not in the centre of the forward face of the arm but merges integrally with, and at that edge of the arm near, the fabric.

At the alignment station for the two weft loops picked up and carried forward by their respective weft hooks or hooked member, as described, there is provided a weft loop positioning and alignment device comprising a small vertical plate 40. The plate 40 is provided with an opening 41 extending through it and positioned in the path of the selvedge thread needle 17, and the plate is further provided with a rearwardly projecting nose 42 spaced for a small distance on that side of the opening 41 remote from the edge of the fabric.

As seen more especially in Figure 8, weft loops carried forward to the alignment station at which said device is positioned are held by their respective weft hooks 14a and 15 so that portions of the openings through these loops are in alignment with each other and with the opening 41 in the plate 40, and the nose 42 serves to space the sides of the lower weft loop apart to prevent them closing together and failing to present openings through which the selvedge thread needle can pass and serves also to position these loops as aforesaid in alignment with the opening 41.

It will be appreciated that although both upper and lower weft loops have portions of their openings in alignment with each other in the direction in which the selvedge thread needle travels through them, the planes of the loops at this time are not parallel since the upper shot or thread of the upper weft loop is held in the rear of the lower thread or shot thereof either by the upper weft needle or by separating means in the form of a lever arm 53, as will be later described, and the plane of this loop is hence inclined rearwardly from the vertical rear face of the stationary positioning plate 40, whilst the lower weft loop is held against the rear face of the stationary posi-

tioning plate 40 and is hence in a vertical, or approximately vertical, plane.

In order to ensure that the lower weft loop and the lower thread of the upper weft loop are held firmly against the rear face of the plate 40 at the alignment station, an auxiliary presser member 32 is secured to the arm 38 of the lower weft hook 15. This auxiliary presser member 32 may take the form of a plate mounted in a vertical, or approximately vertical, plane the lower portion of the plate being formed as a cranked bracket for securing to the arm 38, and the forward edge of the plate at the lower portion thereof being approximately parallel to the length of the arm 38.

The upper forward edge of the plate is curved backwardly, as seen at 43, and terminates in an upstanding abutment 44, this particular form of edge being adopted to assist the upward and forward motion which it is required to give to the lower weft loop. Should the lower shot of the lower weft loop face engage the curved portion of the edge 43 in the travel of the lower weft hook 15 towards the alignment station, this shot is guided upwardly by the curved edge so that when the loop is held at the alignment station, this shot and both shots of the upper loop are both held by the abutment edge 44 against the return face of the plate 40 at the proper height with respect to the opening 41 in the plate.

On the side of the weft loop alignment and positioning device remote from the weft needles is provided a selvedge thread hook 19, for convenience referred to as the selvedge hook. The selvedge hook is pivotally mounted on a vertical spindle 45, itself supported in bearings in a supporting framework 46, the upper part of which is seen in Figure 4.

The selvedge hook is so positioned that it is closely adjacent to the path of the selvedge thread needle 17 so that as it oscillates back and forth on its pivotal mounting 45 it can pass between the selvedge thread and the needle and engage and retain a loop of this thread, as already described. Endwise movement is also imparted to the mounting spindle 45 of the selvedge hook so that when the latter is executing a stroke away from the edge of the fabric it is moved downwardly, and when executing the return stroke towards the edge of the fabric it is moved upwardly thereby facilitating the engagement, retention and subsequent release of loops of selvedge thread, as previously described. It will be appreciated that since the position of the weft loops at the alignment station is level with the stationary stuffer warps of fabric, as seen in Figure 8, it is necessary that in carrying the weft loops to the alignment station the upper weft hook should fall somewhat in its forward travel, whilst the lower weft hook should similarly rise by a corresponding amount. In order to accomplish this the spindle 47 upon which the upper weft hook is mounted, which spindle is supported in suitable bearings in the supporting frame 46, is moved endwise by a mechanism shown in detail in Figure 5.

The spindle 47 is spring-loaded in an upward direction by means of a coiled compression spring 48 acting between a collar 49 fixed on the spindle 47 and the upwardly directed face of the supporting frame 46 bordering on the lower bearing for the spindle. Intermediate the collar 49 and the outer bearing for the spindle there is fixed to the spindle a face cam 50 the upper cam face of which 75 co-operates with a fixed projection 51 secured to

the supporting frame 46 so that as the spindle turns, in moving the upper weft hook forwardly from the weft needles to the alignment station, the spindle 47 is depressed against the pressure of the coiled spring 48.

In the case of the lower weft hook the position of the pivotal axis on which its arm 38 is mounted is such that it is spaced forwardly from the weft needles so that the nose 39 of the lower weft hook executes a rising arcuate path of travel from the lower weft needle towards the alignment station.

In order to prevent weft loops picked up by the weft hooks from slipping over the upper ends of the arm 38 or the lug 34, the respective noses 39 and 35 stand out from abutment faces formed by the forward faces of the arm 38 and the lug 34 so that the weft loops picked up are retained against these abutment faces at the bases of their respective noses.

It will be understood that in weaving a pile fabric where it is required to insert pile between split portions of the upper double shot weft it is necessary to provide means for maintaining separation between the two weft shots constituting the double upper weft shot prior to insertion of the pile. In the employment shown in the drawings such means may conveniently take the form of a lever arm 52 pivoted on a horizontal axis to the guide block at 53 and actuated by a link 54 connected to an extension arm 55 of the lever. The lower end of the lever arm 52, when in its rearmost position, is such as to engage and obstruct the passage of weft threads carried forward from the upper weft needle towards the alignment station by the upper weft hook. Actuation of the link 54 is arranged to permit the upper weft needle to carry a weft thread forwards towards the alignment station and position this beneath the nose 42 of the alignment and positioning device whilst the upper weft needle remains in position in its guide opening. Prior to retraction of the upper weft needle the lever arm 52 is moved to its lower position by the link 54 so that when the upper weft needle is retracted a single shot of weft is maintained level with the rear face of the lever arm 52, thus providing a wide horizontal separation between the alignment station and the lever arm 52 into which the pile can be inserted in the known manner of an Axminster spool loom. After such insertion the lever arm 52 is moved to release the upper shot of weft.

The positioning plate 40 may be provided with a groove 56 in the side wall of the opening 41 nearest the edge of the fabric in order to ensure that retained loops of selvedge thread, such as that shown at 29 diagrammatically in Figure 1, are not deflected out of the path of the selvedge thread needle by local irregularities in the edge of the fabric which these loops enter at their base, such as may be occasioned, for example, by lumps occurring in the jute from which the weft is ordinarily formed.

The driving means for the lower weft hook, the selvedge hook and selvedge thread needle may be as described and illustrated in my co-pending application, Serial No. 760,805, whilst the upper weft hook may be driven by a suitable link pivotally connected to the arm 51, Figure 5, actuated by means of a cam similar to that which drives the lower weft hook. In order to prevent the two weft hooks fouling each other in their travel towards the alignment station, movement is given to one hook, for example the upper, in

advance of the other so that although their paths of travel may have a common portion they do not coincide at such a common portion.

For operating the separating device for splitting apart the upper weft, the link 54 may be connected to a cam-operated lever moving in the required time relation to the other parts of the loom.

The sequence of operations of the various elements constituting the selvedge forming mechanism is such that the method of the invention, as hereinbefore set forth, is carried out, such time relation being achieved with the driving mechanism described and illustrated in my co-pending application, Serial No. 760,805, aforesaid.

The selvedge thread is supplied to the selvedge thread needle from a bobbin or equivalent bulk thread carrier mounted in any convenient position at the rear of the loom, suitable tensioning means of known type being provided between the bobbin or carrier and the needle.

I claim:

1. In the manufacture of a woven fabric in which a pair of double shots of weft are inserted by a pair of weft needles between each shedding operation of the warps, a method of binding in such double shots of weft to form a selvedge edge at the edge of the fabric remote from the edge at which the weft needles first enter the fabric, which method comprises the steps of inserting a loop of selvedge thread from a bulk thread carrier through a pair of weft loops, holding said inserted selvedge thread loop in such position that it is looped around the line defining the path of its insertion, inserting the next succeeding selvedge thread loop through the next succeeding pair of weft loops and through the selvedge thread loop last inserted, and subsequently releasing the latter.
2. In or for a loom of the kind wherein double shot weft are inserted in pairs through the warps by a pair of weft needles selvedge forming mechanism comprising a selvedge thread needle adapted to carry a selvedge thread, said selvedge thread needle being mounted in a guide, means for reciprocating the needle back and forth transversely to the weft, weft hook means comprising a pair of hooked members, said hooked members being mounted for movement transversely to the weft enabling them to carry weft threads from the weft needles towards a weft loop and selvedge thread loop alignment station at which weft loops carried by said weft hook means are held with portions of their openings in alignment with each other, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries, thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

3. In or for a loom of the kind wherein double shot weft are inserted in pairs through the warps by a pair of weft needles selvedge forming mechanism comprising a selvedge thread needle adapted to carry a selvedge thread, said selvedge thread needle being mounted in a guide, means for reciprocating the needle back and forth transversely to the weft, said weft needles each having a gap in one side at or near the leading end of each needle, so that at each of said gaps the weft thread is spaced away from the base of the gap, and is engageable to be drawn away from the associated weft needle by weft hook means moving transversely thereto, said weft hook means comprising a pair of hooked members, said hooked members being mounted for movement transversely to the weft enabling them to carry weft threads from the weft needles towards a weft loop and selvedge thread loop, alignment station at which weft loops carried by said hooked members are held with portions of their openings in alignment with each other, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries, thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

4. In or for a loom of the kind wherein double shot weft are inserted in pairs through the warps by a pair of weft needles selvedge forming mechanism comprising a selvedge thread needle adapted to carry a selvedge thread, said selvedge thread needle being mounted in a guide, means for reciprocating the needle back and forth transversely to the weft, weft hook means comprising a pair of hooked members, said hooked members being mounted for movement transversely to the weft enabling them to carry weft threads from the weft needles towards a weft loop and selvedge thread loop, alignment station at which is provided a stationary member, said stationary member having an opening extending through it in the path of the selvedge thread needle and having a weft loop positioning and parting element so as to split apart the weft loops carried thereto by weft hook means and position said weft loops with portions of their openings in alignment with each other, a selvedge hook positioned closely adjacent the path of the selvedge thread needle and on the side of the alignment station remote from the weft needles said selvedge hook being movably mounted to execute movements transversely to the selvedge threaded needle and pass between said needle and the selvedge thread it carries, thereby enabling the selvedge hook to engage and temporarily retain a loop of selvedge thread from the selvedge thread needle on one stroke and release this loop on the return stroke, these movements being timed in relation to the

reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

5. In or for a loom of the kind wherein double shot weft are inserted in pairs through the warps by a pair of weft needles selvedge forming mechanism comprising a selvedge thread needle adapted to carry a selvedge thread, said selvedge thread needle being mounted in a guide, means for reciprocating the needle back and forth transversely to the weft substantially parallel to the edge of the fabric, said weft needles each having a gap in one side at or near the leading end of each needle so that at each of said gaps the weft thread is spaced away from the base of the gap, and is engageable to be drawn away from the associated weft needle by weft hook means moving transversely thereto, said weft hook means comprising a pair of hooked members, said hooked members being mounted for movement transversely to the weft in a direction enabling them to carry weft threads from the weft needles towards the fall of the fabric, a weft loop and selvedge thread loop alignment station at which is provided a stationary member supported adjacent to the fall of the fabric, said stationary member having an opening extending through it in the path of the selvedge thread needle, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

6. In or for a loom of the kind specified wherein there is provided a pair of weft inserting needles mounted one above the other with respect to thickness of the fabric, selvedge forming mechanism comprising a selvedge thread needle adapted to carry a selvedge thread, said selvedge thread needle being mounted in a guide, means for reciprocating the needle back and forth transversely to the weft substantially parallel to the edge of the fabric, said weft needles each having a gap in one side at or near the leading end of each needle, so that at each of said gaps the weft thread is spaced away from the base of the gap, and is engageable to be drawn away from the associated weft needle by weft hook means moving transversely thereto, said weft hook means comprising a pair of hooked members, one for engaging weft from the upper weft needle, and one for engaging weft from the lower weft needle, said hooked member being mounted for

11

movement transversely to the weft in a direction enabling them to carry weft threads from the weft needles towards the fall of the fabric, the upper hooked member being pivotally mounted on a vertical axis, the lower hooked member being pivotally mounted on a horizontal axis, a weft loop and selvedge thread loop alignment station at which is provided a stationary member supported adjacent to the fell of the fabric, said stationary member having an opening extending through it in the path of the selvedge thread needle, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

7. In or for a loom of the kind specified wherein there is provided a pair of weft inserting needles to carry weft threads from the weft needles, selvedge forming mechanism comprising a selvedge thread needle adapted to carry a selvedge thread, said selvedge thread needle being mounted in a guide, means for reciprocating the needle back and forth transversely to the weft substantially parallel to the edge of the fabric, said weft needles each having a gap in one side at or near the leading end of each needle so that at each of said gaps the weft thread is spaced away from the base of the gap and is engageable to be drawn away from the associated weft needle by weft hook means moving transversely thereto, said weft hook means comprising a pair of hooked members, said hooked members being mounted for movement transversely to the weft in a direction enabling them to carry weft threads from the weft needles towards the fell of the fabric, the upper hooked member being pivotally mounted on a vertical axis and adapted to fall in its travel towards the fell of the fabric, the lower hooked member being pivotally mounted on a horizontal axis positioned forwardly of weft needles so that the lower hooked member is thereby adapted to rise in its travel towards the fell of the fabric, each of said hooked members being formed with a nose projecting in the forward direction of travel of said hooked members and standing out from a surface at the base of the nose, said surface constituting an abutment for the weft thread so as to prevent displacement of the weft thread rearwardly and down a supporting arm carrying the hooked member, a weft loop and selvedge thread loop alignment station at which is provided a stationary member supported adjacent to the fell of the fabric, said stationary member having an opening extending through it in the path of the selvedge thread needle, a selvedge hook positioned closely adjacent the path

of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

8. In or for a loom of the kind specified wherein there is provided a pair of weft inserting needles mounted one above the other with respect to thickness of the fabric, selvedge forming mechanism comprising a selvedge thread needle adapted to carry a selvedge thread, said selvedge thread needle being mounted in a guide, means for reciprocating the needle back and forth transversely to the weft substantially parallel to the edge of the fabric, said weft needles each having a gap in one side at or near the leading end of each needle so that at each of said gaps the weft thread is spaced away from the base of the gap and is engageable to be drawn away from the associated weft needle by weft hook means moving transversely thereto, said weft hook means comprising a pair of hooked members, said hooked members being mounted for movement transversely to the weft in a direction enabling them to carry weft threads from the weft needles towards the fell of the fabric, a weft loop and selvedge thread loop alignment station at which is provided a stationary member supported adjacent to the fell of the fabric, said stationary member having an opening extending through it in the path of the selvedge thread needle, a selvedge hook positioned closely adjacent the path of the selvedge thread needle and on the side of the alignment station remote from the weft needles, said selvedge hook being movably mounted on a pivotal axis to execute movements transversely to the selvedge threaded needle and pass between said needle and the selvedge thread it carries, said selvedge hook being operatively connected to it, means for moving it in a plane parallel to that of the fabric and away from and towards the edge thereof, such movement being accompanied by respective falling and rising of the selvedge hook enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

9. In or for a loom of the kind specified wherein there is provided a pair of weft inserting needles mounted one above the other with respect

to thickness of the fabric, selvedge forming mechanism comprising a selvedge thread needle adapted to carry a selvedge thread, said selvedge thread needle being mounted in a guide means for reciprocating the needle back and forth transversely to the weft substantially parallel to the edge of the fabric, said weft needles each having a gap in one side at or near the leading end of each needle so that at each of said gaps the weft thread is spaced away from the base of the gap and is engageable to be drawn away from the associated weft needle by weft hook means moving transversely thereto, said weft hook means comprising a pair of hooked members, one for engaging weft from the upper weft needle, and one for engaging weft from the lower weft needle, said hooked members being mounted for movement transversely to the weft in a direction enabling them to carry weft threads from the weft needles towards the fell of the fabric, the upper hooked member being pivotally mounted on a vertical axis, the lower hooked member being pivotally mounted on a horizontal axis, a weft loop and selvedge thread loop alignment station at which is provided a stationary member supported adjacent to the fall of the fabric, said stationary member having an opening extending through it in the path of the selvedge thread needle, and having a weft loop positioning and parting element comprising a projection extending rearwardly from the rear face of said stationary member, said projection being tapered in said rearward direction and positioned laterally of said opening so as to split apart the weft loops carried thereto by the weft hook means and position said weft loops with portions of their openings in alignment with each other and with the opening in said stationary member, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations.

10. In or for a loom of the kind specified wherein there is provided a pair of weft inserting needles mounted one above the other with respect to thickness of the fabric, selvedge forming mechanism comprising a selvedge thread needle adapted to carry a selvedge thread, said selvedge thread needle being mounted in a guide means for reciprocating the needle back and forth transversely to the weft substantially parallel to the edge of the fabric, said weft needles each having a gap in one side at or near the leading end of each needle so that at each of said gaps the weft thread is spaced away from the base of the gap and is engageable to be drawn away from the associated weft needle by weft hook means moving transversely thereto, said weft hook means

comprising a pair of hooked members, one for engaging weft from the upper weft needle, and one for engaging weft from the lower weft needle, said hooked members being mounted for movement transversely to the weft in a direction enabling them to carry weft threads from the weft needles towards the fell of the fabric, the upper hooked member being pivotally mounted on a vertical axis, the lower hooked member being pivotally mounted on a horizontal axis, a weft loop and selvedge thread loop alignment station at which is provided a stationary member supported adjacent to the fell of the fabric, said stationary member having an opening extending through it in the path of the selvedge thread needle, and having a weft loop positioning and parting element comprising a projection extending rearwardly from the rear face of said stationary member, said projection being tapered in said rearward direction and positioned laterally of said opening so as to split apart the weft loops carried thereto by the weft hook means and position said weft loops with portions of their openings in alignment with each other and with the opening in said stationary member, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge thread needle and is released by the selvedge hook in the next succeeding cycle of operations, said stationary member at the alignment station having a groove in the wall of its opening, said groove being positioned to receive the selvedge threads of said previously inserted selvedge thread loop and prevent displacement of said previously inserted loop out of alignment with the path of the needle.

11. In or for a loom of the kind specified wherein there is provided a pair of weft inserting needles mounted one above the other with respect to thickness of the fabric, selvedge forming mechanism comprising a selvedge thread needle adapted to carry a selvedge thread, said selvedge thread needle being mounted in a guide block having a guide opening extending substantially parallel to the edge of the fabric, means for reciprocating the needle back and forth in the guide opening transversely to the weft substantially parallel to the edge of the fabric, said weft needles each having a gap in one side at or near the leading end of each needle, so that at each of said gaps the weft thread is spaced away from the base of the gap, and is engageable to be drawn away from the associated weft needle by weft hook means moving transversely thereto, said weft hook means comprising a pair of hooked members, one for engaging weft from the upper weft needle, and one for engaging weft from the lower weft needle, said hooked members being mounted for movement transversely to the weft

15

in a direction enabling them to carry weft threads from the weft needles towards the fell of the fabric, said guide block also having guide openings positioned to receive the leading ends of the weft needles so as to hold these against appreciable lateral deflection in the weft thread engaging action of said hooked members, and having further guide openings positioned to receive said hooked members at the rearward part of their paths of travel, a weft loop and selvedge thread loop alignment station at which is provided a stationary member supported adjacent to the fell of the fabric, said stationary member having an opening extending through it in the path of the selvedge thread needle, a selvedge hook positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge hook being in such position that it presents an opening in the path of the selvedge thread needle and is released by the selvedge hook in the next succeeding cycle of operations.

12. In or for a loom of the kind specified wherein there is provided a pair of weft inserting needles mounted one above the other with respect to thickness of the fabric, said needles being adapted to insert a pair of double shots of weft, one such double shot being associated with each needle, the upper double shot of weft serving to secure inserted pile against withdrawal from the weft and warps of the fabric, and the lower double shot serving to provide a relatively firm base forming a backing for the fabric, selvedge forming mechanism comprising a selvedge thread needle adapted to carry a selvedge thread, said selvedge thread needle being mounted in a guide, means for reciprocating the needle back and forth transversely to the weft, weft hook means comprising a pair of hooked members, said hooked members being mounted for movement transversely to the weft enabling them to carry weft threads from the weft needles towards a weft loop and selvedge thread loop alignment station at which weft loops carried by said weft hook means are held, with portions of their openings in alignment with each other positioned closely adjacent the path of the selvedge thread needle and on the side of the alignment station remote from the weft needles, said selvedge hook being movably mounted to execute movements transversely to the selvedge threaded needle and pass between said needle and the selvedge thread it carries thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and

16

the previously inserted selvedge thread loop, said loop of selvedge thread held by the selvedge hook being in such position that it presents an opening in the path of the selvedge thread needle and is released by the selvedge hook in the next succeeding cycle of operations, separating means for the weft carried by the upper weft needle, said separating means comprising a returning member mounted intermediate the weft needles and the alignment station, and having associated therewith means adapted to actuate it in timed relation to the weft hook means between two positions, in one of which it allows the passage of weft carried by the upper hooked member, and in the other of which it obstructs the movement of the weft with the upper hooked member, the movement of the retaining member being such that it is brought into the obstructing position after forward movement of the upper hooked member and before retraction of the upper weft needle back through the fabric so as to provide a split upper weft loop within the fabric to facilitate the insertion of pile.

13. In or for a loom of the kind specified wherein there is provided a pair of weft inserting needles mounted one above the other with respect to thickness of the fabric said needles being adapted to insert a pair of double shots of weft, one such double shot being associated with each needle, the upper double shot of weft serving to secure inserted pile against withdrawal from the weft and warps of the fabric, and the lower double shot serving to provide a relatively firm base forming a backing for the fabric, selvedge forming mechanism comprising a selvedge thread needle adapted to carry a selvedge thread, said selvedge thread needle being mounted in a guide block having a guide opening extending substantially parallel to the edge of the fabric, means for reciprocating the needle back and forth in the guide opening transversely to the weft substantially parallel to the edge of the fabric, said weft needles each having a gap in one side at or near the leading end of each needle, so that at each of said gaps the weft thread is spaced away from the base of the gap and is engageable to be drawn away from the associated weft needle by weft hook means moving transversely thereto, said weft hook means comprising a pair of hooked members, said hooked members being mounted for movement transversely to the weft enabling them to carry weft threads from the weft needles towards a weft loop and selvedge thread loop alignment station at which weft loops carried by said weft hook means are held with portions of their openings in alignment with each other, a selvedge hook positioned closely adjacent the path of the selvedge thread needle, and on the side of the alignment station remote from the weft needles, said selvedge hook being movably mounted to execute movements transversely to the selvedge threaded needle and pass between said needle and the selvedge thread it carries, thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said loop of selvedge thread held by the selvedge hook being in such position that it presents an opening in the path of the selvedge

thread needle and is released by the selvedge hook in the next succeeding cycle of operations, separating means for the weft carried by the upper weft needle, said separating means comprising a retaining member in the form of a pivotal arm mounted intermediate the weft needles and the alignment station on the guide block, and having associated therewith means adapted to actuate it in timed relation to the weft hook means between two positions, in one of which, it allows the passage of weft carried by the upper hooked member, and in the other of which it obstructs the movement of the weft with the upper hooked member, the movement of the retaining member being such that it is brought into the obstructing position after forward movement of the upper hooked member and before retraction of the upper weft needle back through the fabric so as to provide a split upper weft loop within the fabric to facilitate the insertion of pile.

14. In or for a loom of the kind wherein double shot weft are inserted in pairs through the warps by a pair of weft needles selvedge forming mechanism comprising a selvedge thread needle adapted to carry a selvedge thread, means for reciprocating the needle back and forth transversely to the weft, weft hook means mounted for movement transversely to the weft in a direction enabling them to carry weft threads from the weft needles towards a weft loop and selvedge thread loop alignment station at which weft loops carried by said weft hook means are held with portions of their openings in alignment with each other, a selvedge hook positioned closely adjacent the path of the selvedge thread needle and on the side of the alignment station remote from the weft needles, said selvedge hook being movably mounted to execute movements and pass between said needle and the selvedge thread it carries, thereby enabling the selvedge hook to engage and temporarily retain a loop of selvedge thread from the selvedge thread needle on one stroke and release this loop on the return stroke, these movements being timed in relation to the reciprocation of the selvedge thread needle so that a loop of selvedge thread is passed by the selvedge thread needle through a pair of weft loops and the previously inserted selvedge thread loop, said

loop of selvedge thread held by the selvedge hook being in such position that it presents an opening in the path of the selvedge thread needle and is released by the selvedge hook in the next succeeding cycle of operations.

15. In the manufacture of a woven fabric in which a pair of double shots of weft are inserted by a pair of weft needles between each shedding operation of the warps, a method of binding in such double shots of weft to form a selvedge edge at the edge of the fabric remote from the edge at which the weft needles first enter the fabric, which method comprises the steps of withdrawing a loop of weft thread from each weft needle; moving said weft loops towards the fell of the fabric; holding said weft loops at a position adjacent to the fell of the fabric with portions of the loops in alignment with each other; inserting a loop of selvedge thread from a bulk thread carrier through said aligned weft loop portions; holding said inserted selvedge thread loop in such position that it is looped around the line defining the path of its insertion; releasing the weft loops; inserting the next succeeding selvedge thread loop through the next succeeding pair of weft loop portions which are withdrawn from the weft needles, moved towards, and held in alignment with each other adjacent to the fell of the fabric in a like manner to the first said pair, and through the selvedge thread loop last inserted; releasing the latter and the second said pair of weft loops.

PHILIP WORTH ROBINSON.
